UNITED STATES PATENT OFFICE.

HARRY WALKER, OF DENVER, COLORADO, ASSIGNOR TO CLARKE & WALKER, OF SAME PLACE.

CIGAR-BOX.

SPECIFICATION forming part of Letters Patent No. 394,945, dated December 18, 1888.

Application filed March 21, 1888. Serial No. 268,005. (No model.)

To all whom it may concern:

Be it known that I, HARRY WALKER, of the city of Denver, in the county of Arapahoe and State of Colorado, have invented a new Ap-
pliance for Cigar-Boxes, the same serving to keep the cigar moist and fresh; and I do hereby declare that the following is a full and exact description thereof, reference being had to the accompanying drawings, and to the let-
ters of reference marked thereon.

This invention relates to cigar-boxes.

The object is, without material increase in bulk and in a ready, efficient, and inexpensive manner, to produce a cigar-box in which the contents may be kept moist, so that cigar manufacturers and dealers may be enabled to keep their goods fresh in boxes of usual size and appearance and sell them without increase of price.

The invention consists, essentially, in a cigar-box provided with the usual movable lid, hinged or nailed, but with a perforated bottom and with a flap or cover arranged beneath this bottom, leaving a shallow chamber between the flap and the bottom, where a moistened pad is to be inserted.

I have illustrated the invention in the accompanying drawings, in which—

Figure 1 is a perspective view of a box made in accordance with my invention, the lid being open to show the interior. Fig. 2 is another perspective view of the box, the flap being raised to show the bottom; and Fig. 3 is a transverse section of the box. Fig. 4 is a sectional view illustrating the lower portion of the bottom of the box with a strip of tin-foil on the bottom turned up. Fig. 5 is a sectional view of another common form of box in which the tray is dispensed with, the moistened pad and the two strips of tin-foil being shown turned up in order to illustrate their proper relation.

In the drawings, A represents a cigar-box, of wood or other suitable material, provided with a movable lid, in the present instance shown as hinged.

The box proper here shown is of ordinary form—namely, having a tray located at about the center for the purpose of separating layers of cigars.

No invention is claimed in the construction of the box otherwise than in the moistening device, and I do not of course wish to be un-

derstood as limiting myself to any special form of box.

The bottom of the box a' is, as shown, provided with perforations, and the cover or flap a³ is hinged to the bottom, and so placed in relation thereto as to leave a space for the reception of a moistened pad, a², of any suitable material—such as blotting-paper, cloth, or the like—which will absorb and hold a suitable quantity of water to keep the contents of the box moist. The flap when closed rests in an indentation or countersink in the bottom of the box to present a flat surface. The only additional depth of the box over ordinary boxes is given by the space between the perforated bottom and the flap, and this is not sufficient to add materially to the size.

The bottom of the box is provided on its upper and lower faces with strips of tin-foil, b, which serve to prevent the wood from warping or from other injury incident to placing the same in contact with the moistened pad.

C represents a tray, which may, if desired, be employed in the box. This tray rests upon cleats c, fixed to the sides and ends of the box, and its bottom is preferably perforated, as shown, to allow moisture to rise from the pad and keep the cigars placed on the tray fresh.

It will be found in practical use that a box made as herein described possesses great advantages over one in which a damp pad is slid into a shallow chamber at the bottom of a box, because of the great difficulty of successfully sliding a moistened fabric into a narrow space; and it also possesses great advantage in point of cost and convenience over one in which the moistened pad is put on a tray and placed in an opening in the bottom of the box.

Having thus fully described my invention, what I claim as new, and desire to secure by Letters Patent, is—

A cigar-box consisting of the ordinary box with a hinged or other lid, but with its bottom perforated, and with a hinged flap, leaving a shallow compartment between the flap when closed and the perforated bottom, a moistened pad to be interposed between the flap and the bottom, substantially as described.

Witnesses: HARRY WALKER,
JOHN F. SHOFROTH,
PLATT ROGERS.
